UNITED STATES PATENT OFFICE.

JACOB GUT, OF CLEVELAND, OHIO.

AUTOMATIC TRAIN-STOP.

1,323,627.

Specification of Letters Patent.

Patented Dec. 2, 1919.

Application filed May 15, 1918. Serial No. 234,639.

To all whom it may concern:

Be it known that I, JACOB GUT, a citizen of the United States, residing at Cleveland, in the county of Cuyahoga and State of 5 Ohio, have invented certain new and useful Improvements in Automatic Train-Stops, of which the following is a specification.

This invention relates to automatic train-stops, and particularly to electrically controlled devices for setting the brakes on railway trains and cutting off the steam to the locomotive under danger conditions. The apparatus includes means for first closing the throttle, and then in due time applying 15 the brakes, to avoid the shock of applying the brakes when running at high speed.

The invention is in some respects a modification of or improvement on an apparatus for a similar purpose shown in my U. S. 20 Patent 1,238,512 dated Aug. 28, 1917.

In the accompanying drawings

Figure 1 is a combined section and diagram of the valve and the controlling circuits;

25 Fig. 2 is an elevation of the cab devices; Fig. 3 is a top plan view of the same; Fig. 4 is a side elevation.

In the drawings, 52 indicates a motor case and 47 a valve casing mounted in the cab 30 adjacent to the throttle lever which consists of parts 8 and 9 to be hereinafter described, the lever being connected by a rod 11 and other parts in the usual way to a throttle valve (not shown), and the valve 35 casing 47 is connected to the air line and the engineer's valve 79 (see Fig. 2) in a manner to be described. The apparatus acts to operate the throttle lever, and to set the brakes, and the control will be further 40 described and will be understood in connection with the following description of the operation:

82 (see Fig. 4) indicates an electro-magnet under the track which may be energized 45 from any signal station or otherwise, and it acts to attract an armature 88 carried in some convenient location under the engine, as by a bracket 91, to which it is pivoted at 89, with the spring 90 to normally 50 hold it out of action. This armature, or the end part 81 thereof, co-operates with an electromagnet 80, carried by the engine, and acts to close a cab circuit which includes 55 a battery 67, lines 55, 55^a, 59, 61, switch 60 and the coils of said magnet, the construction being such that when the mag-

net is energized it will remain so and hold the circuit closed even after passing the track magnet 82, until released by opening the switch 60. The armature 81 carries a 60 switch piece 108 which when lifted connects the contacts 100 and 101, thereby closing a circuit which includes the lines 62, 62^a and 63 and contacts 93 and 94 which are electrically connected by an insulated conduct- 65 ing strip 103 which laps both of said contacts and is mounted on the quadrant gear 49^a, the circuit including the field of the electric motor 51 the armature of which carries a gear 50 in mesh with the quadrant 70 gear 49^a; and when the motor is actuated it turns the quadrant gear to the right as shown in Fig. 1. This gear is connected to the stem of a valve 48, which when it is turned as described will connect an exhaust 75 port 70 to the passages 46^b, 46^a and 46, the latter opening from a chamber 110 in the valve casing 47 at one side of a differential piston 38^a, and air pressure in the chamber 111 at the other side of said piston will 80 force the latter outwardly when the compressed air is so released from the chamber 110 through the passages and the port 70 to the atmosphere. The piston 38^a is attached to and carries with it a D valve 34 which by 85 such movement connects a port 41 to an exhaust passage 39 which is open to the atmosphere and releases air from cylinder space 42 and at the same time uncovers a port 40 which admits compressed air from 90 the chamber 111 to the space 43 below the piston 112. Compressed air is supplied to the chamber 111 from an air pipe 22 through a port 28, chamber 27 and port 30. When the air is so supplied to the chamber 43 it 95 forces the piston 112 outwardly. The rod 113 of this piston carries a pivot stud 13 which works in a T-groove 12 in a swinging section 8 of the throttle lever, which section is connected to the throttle rod 11 by a 100 pivot 10, the section 8 swinging on a pivot 6 secured to the throttle lever 9 which is pivoted to a bracket 68 on the engine frame. If the throttle is open, outward movement of the piston rod 113 and its stud 13 will 105 act as a sliding cam to swing the section 8 inwardly, as shown in dotted lines in Fig. 3, thereby shifting the throttle rod 11 and closing the throttle valve. It will be noted that when the piston rod 113 is in normal 110 position the pivot stud 13 of the section 8 is concentric with the pivot 68 of the lever

9, so that when the lever is pulled back to open the throttle the section 8, by reason of the connection at 6, will take the same movement on the pivot 13, and thus open the 5 throttle, but when the piston rod 113 is advanced as described the section 8 will swing to close the throttle, the lever remaining in original position until operated by hand.

It will be seen, therefore, that when the 10 motor 51 is energized the throttle will be closed. With respect to the brake operation, which afterward takes place, the operation is as follows:

When the quadrant gear 49^a is swung 15 fully to the right, in Fig. 1, a circuit is closed to the other motor 51^a. This circuit includes two contacts 54, which are wiped by the conducting strip 103, and lines 62 and 62^b to a governor 71 mounted on the 20 engine axle and thence to ground, and on the other side, from the battery 67 through lines 56, 63 and 65 and contacts 96 and 95 to ground. The motor circuit remains open, however, until contacts 115 and 116, forming a part of the governor mechanism 71, 25 are closed, the contact 115 being connected to the governor balls 117 which revolve with the axle. When the engine is running at considerable speed these contacts will be held open by the centrifugal action, so that 30 the brake service to be described will not occur until the speed has been sufficiently decreased to close the contacts 115 and 116. This prevents applying the brakes too 35 quickly or when the speed is too great. When the motor is finally energized the pinion 50^a on its armature shaft turns a quadrant gear 49 to the left. This gear is attached to the stem of a valve 48^a, and 40 when this valve is turned it connects a port 69, open to the atmosphere, to a port 120 and releases air from a chamber 109 at one side of a differential piston 38, which is then shifted outwardly by air pressure in 45 the chamber 111, carrying with it a D-valve 33. This action connects a chamber 75 to ports 31 and 32, the latter leading to the atmosphere, thereby releasing air from the chamber 75 behind a tubular valve 23 which 50 controls the passage of air from the air pipe 22 to the train pipe 17. The valve 23 shifts inwardly under the pressure in the train pipe, closing the port 121 which connects the pipes 22 and 17, and opening an exhaust 55 port 21. This exhaust port 21 is controlled by what is known as an "interrupter", adapted to prevent the too rapid escape of air from the train pipe. This interrupter includes a tubular differential valve 20 which has a port 122 therein to coöperate with a V-shaped port 123, just below it, which opens to the air. When the compressed air rushes through the port 21 the impact shifts the valve 20 outwardly and 60 reduces the effective escape opening and 65

thereby the velocity. When the velocity is diminished sufficiently the air pressure in the chamber 19 at the opposite side of the valve 20, which is connected by a by-pass 150 with the train pipe, will shift the valve 70 20 inwardly, owing to the greater area of its outer end; and thus the valve 20 will shift to and fro, thereby exhausting the air from the train pipe gradually and permitting the gradual application of the 75 brakes.

To prevent the air in the train pipe from being entirely exhausted, an auxiliary piston 26 is provided in the chamber 27. This piston has a rod 24 projecting toward the 80 tubular valve 23, and when the valve closes the piston is shifted inwardly. When the pressure in the train pipe is sufficiently reduced to compensate for the difference in area of the valve 23 and the piston 26, the 85 air pressure entering the chamber 27 through the port 28 acts on said piston to shift the valve 23 sufficiently to close the exhaust 21, the port 121 remaining also closed as though the engineer's valve were 90 in lap position.

When the motors 51 and 51^a are reversed by a method to be presently described they restore the valves 48 and 48^a to original position, and air pressure from the chamber 95 27 is admitted through the port 53 to the chambers 109 and 110 against the larger surfaces of the differential pistons 38 and 38^a thereby forcing them inwardly and exhausting the air from the chamber 43 and 100 admitting the air to the chamber 42, as well as admitting the air through the passages 30 and 31 to the chamber 75, thereby shifting the piston 112 inwardly and also restoring the normal pressure in the chamber 105 75, shifting the tubular valve 23 to original position, opening the port 121 to the train pipes and by restoring the pressure in train pipes the brakes will be released and all the parts will resume their original position. 110 This reversal of the motors is effected by opening the switch 60 which deenergizes the magnet 80, permitting the armature 81 to drop thereby opening the contacts 100 and 101 and closing the contacts at 98 and 99 115 thereby reversing the current from the battery, through the lines 57 and 57^a and contacts 92 and 96. It will be noted that in one position of the segment 103 it closes with contacts 93 and 94, and in the other 120 125 position with contacts 92 and 93, and likewise the contact strip 102, which is carried by the segment 49, closes in one position with the contacts 96 and 97, on the armature frames, whereby the circuits and the 125 motors are reversed in the manner described.

I claim:

1. In an engine controlling mechanism, the combination with a throttle lever having a swinging bar attached thereto, of a fluid 130

pressure actuated electrically-controlled piston connected to said bar and adapted to swing the same, independent of the lever, in a direction to close the throttle.

5 2. The combination with a throttle lever having a shiftable connection to the throttle rod, of a fluid pressure-actuated piston slidably engaging said connection and adapted to shift the same in a direction to close the 10 throttle, and means to control the actuation of said piston.

15 3. The combination with a pivoted throttle lever, of an auxiliary bar pivoted to said lever and connected to the throttle rod, a fluid pressure actuated device having a sliding pivotal connection to said bar and adapted to swing the same, independent of the lever, in a direction to close the throttle, when the device is advanced, said pivotal 20 connection being substantially concentric with the pivot of the lever when the device is retracted, and means to control the actuation of said device.

25 4. In a train-controlling mechanism, the combination of a fluid pressure actuated throttling device, a fluid pressure-actuated device controlling the air brakes, a valve controlling the admission of fluid pressure to each of said devices, an electric motor operatively connected to each of said valves, and electrically actuated means controlling the 30 operation of each motor.

35 5. In a train controlling mechanism, the combination of a fluid pressure actuated throttling device, a fluid pressure-actuated device controlling the air brakes, a valve controlling the admission of fluid pressure to each of said devices, an electric motor operatively connected to each of said valves, and 40 electrically actuated means controlling the operation of each motor, and speed-controlled means to delay the operation of the motor operating the valve controlling the air brake device until after the operation of 45 the throttling device.

50 6. In an engine controlling mechanism, the combination of a throttling device including a fluid pressure-operated piston, a fluid pressure actuated-valve controlling admission of fluid pressure to opposite sides of said piston, and exhaust therefrom, a turning valve

controlling admission of fluid pressure to said valve, an electric motor geared to said turning valve, and electrically-controlled means to operate said motor. 55

7. In an engine controlling mechanism, the combination of a speed reducing device, air pressure actuated means to operate said device, a valve controlling the air pressure, an electric motor geared to the valve, and electric means controlled by a track device to operate the motor. 60

8. In a train controlling mechanism, the combination of a throttling device, a brake setting device, air pressure-actuated means 65 to operate each device, a valve controlling the air pressure to each of said means, an electric motor operatively connected to each valve, and electric means controlled by a track device to operate both motors. 70

9. In a train controlling mechanism, the combination of a throttling device, a brake setting device, air pressure-actuated means to operate each device, a valve controlling the air pressure to each of said means, a first 75 electric motor operatively connected to the valve related to the throttling device, a second electric motor operatively connected to the valve related to the brake setting device, electric means to close the circuit of the first 80 motor, and means actuated by the first motor to close the circuit of the second motor.

10. In a train controlling mechanism, the combination of a throttling device, a brake setting device, air pressure-actuated means 85 to operate each device, a valve controlling the air pressure to each of said means, a first electric motor operatively connected to the valve related to the throttling device, a second electric motor operatively connected to 90 the valve related to the brake setting device, electric means to close the circuit of the first motor, and means actuated by the first motor to close the circuit of the second motor, and speed controlled means to delay the closing 95 of the circuit of the second motor.

In testimony whereof I do affix my signature in presence of two witnesses.

JACOB GUT.
